OR D 13,356

Mo. 13,356.

Oct. 24 - 1882

UNITED STATES PATENT OFFICE.

JOHN GLEN, OF BROOKLYN, NEW YORK.

DESIGN FOR A PRINTED FABRIC.

SPECIFICATION forming part of Design No. 13,356, dated October 24, 1882.

Application filed September 26, 1882. Term of patent 3½ years.

To all whom it may concern:

Be it known that I, JOHN GLEN, of Brooklyn, Kings county, in the State of New York, have invented a new and original Design for Printed Fabrics; and I do hereby declare that the following specification, taken in connection with the accompanying illustration, forming a part of the same, is a full, clear, and exact description thereof.

10 My design relates particularly to printed fabrics known as "calicoes," although it is equally applicable to silks, woolens, and other fabrics, either printed or woven.

It consists in the representation of leaves, flowers, and vines, as will hereinafter appear.

15 Referring to the illustration, A represents a leaf, and B a spray of flowers. C represents a leaf similar to A, and D a spray of flowers similar to B. E are vines, which extend from 20 leaf to leaf. The leaf A and spray B, or the leaf C and spray D, or both leaves and sprays, may be repeated upon the ground of the fabric, with or without the vines E, to form the pattern.

The fabric may be produced in any preferred 25 variety or combination of colors for giving a desirable effect to the design.

What I claim, and desire to secure by Letters Patent, is—

1. The design for printed and other fabrics, 30 consisting of the leaf A and spray of flowers B, substantially as set forth.

2. The design for printed and other fabrics, 35 consisting of the leaf C and spray of flowers D, substantially as set forth.

3. The design for printed and other fabrics, 40 consisting of the leaves A C and sprays of flowers B D, substantially as set forth.

4. The design for printed and other fabrics, consisting of the leaves A C, sprays of flowers 45 B D, and vines E, substantially as described and shown.

JOHN GLEN.
